UNITED STATES PATENT OFFICE.

ALBERT W. MILLER, OF RIVERSIDE, CALIFORNIA.

DESIGN FOR A LIMB-PROP BRACKET.

SPECIFICATION forming part of Design No. 35,518, dated December 31, 1901.

Application filed October 3, 1901; Serial No. 77,508. Term of patent 14 years.

To all whom it may concern:

Be it known that I, ALBERT W. MILLER, a citizen of the United States, residing at Riverside, in the county of Riverside and State of California, have invented and produced a new and original Design for a Limb-Prop Bracket, of which the following is a specification.

This invention relates to a new and original design for limb-prop brackets, and has for its object to provide a design of this character which shall be both useful and ornamental.

In the drawings, Figure 1 is a perspective view of a bracket embodying the present design. Fig. 2 is a top plan view thereof. Fig. 3 is an end view of the bracket.

Like characters of reference designate corresponding parts in all the figures of the drawings.

The present design embodies a substantially quadrilateral skeleton or frame-like body, the sides of which are rod-shaped or cylindrical. The longitudinal sides 1 are straight and converge inwardly and have their inner ends bowed inwardly in opposite directions, as indicated at 5, and then rise

upwardly and bowed outwardly, as at 6, into an upstanding tongue, the sides of which diverge upwardly and have their upper ends merged into each other in a rounded terminal 7. The opposite end of the frame-like body 30 has superposed straight members 2, which overlap each other and lie in mutual engagement, the outer ends of said end members being bowed and merged into the respective side members of the body, while the inner 35 terminals of said members are bowed into hook-shaped terminals 3, which are reversely disposed and lie wholly within the body or frame, the free extremities of the hooks being pointed, as indicated at 4.

What I claim is—

The design for a limb-prop bracket substantially as shown and described.

In testimony that I claim the foregoing as my own I have hereto affixed my signature in 45 the presence of two witnesses.

ALBERT W. MILLER.

Witnesses:

E. J. BRYAN,

W. J. DINSMORE.
